METHOD AND MEANS FOR REPAIRING
CRACKS IN CASTINGS

Joe Lemos, Salinas, Calif.

Application April 22, 1936, Serial No. 75,861

3 Claims. (Cl. 29—156.4)

This invention appertains to new and useful improvements in means and method for repairing cracks or openings in castings such as automobile engine blocks and heads, as well as other structures of similar formation.

The principal object of the present invention is to provide a method of repairing cracks and castings wherein a cement compound is first inserted in the cracks and subsequently a wedge is driven 10 in the cracks to completely seal the aperture.

Another important object of the invention is to provide means for repairing castings with cracks in the form of a wedge which can be driven into the crack of a casting in such a manner as 15 to completely fill the cracks and overlap the outer confines thereof.

These and various other important objects and advantages of the invention will become apparent to the reader of the following specification.

In the drawings:

Figure 1 represents a fragmentary vertical sectional view through an engine head showing the means for repairing a crack therein.

Figure 2 is a fragmentary horizontal sectional view taken substantially on line 2—2 of Figure 1.

Figure 3 is a fragmentary vertical sectional view through a slightly modified form of the means and method for repairing engine heads.

Figure 4 represents a perspective view of a 30 wedge formed to follow a definite crack.

Figure 5 is a cross-sectional view taken substantially on line 5—5 of Figure 4.

Referring to the drawings, wherein like numerals designate like parts, it can be seen in Figs. 35 1 and 2, that the numeral 5 represents the usual cylinder of an engine construction while the numeral 6 represents the water jacket.

Assuming that the crack is in the water jacket 6, and denoted by the numeral 7, it can be seen 40 that the crack is first spread to receive the cement compound 8, after which the wedge strip 9 is suitably bent and driven into the crack so as to fill the same throughout its entire length and then completely driven in so as to overlap the outside 45 of the crack as suggested in Figure 2, and denoted clearly by the numeral 10.

It is preferable as shown in Figure 1, that the

outer edge portion of the wedge shaped member 9 have a bead-like head 11 which will flatten out over the outer limits of the crack 7. As is shown in Figure 3, the method is somewhat different, in that if the crack is split simply on top of the 5 water jacket 6, it is preferable that openings 12 be bored downward through the side walls and these bores are preferably filled with the cementitious compound 8 as well as the transverse crack in the top of the jacket. After this, the wedge 10 9a with its bead-like edge portion 11a is driven down into the crack and the bead-like edge portion 11a flattens over the outer limits of the crack.

In this connection, it is preferable that the 15 edge portions of the wedge 9a be cut away, as at 13 under the beading 11a so that the upper end portions of the column of cementitious compound 8 will interlock with the wedge 9a, thus serving to retain the wedge permanently in place.

While the foregoing specification sets forth the invention in specific terms, it is to be understood that numerous changes in the shape, size, and materials may be resorted to without departing from the spirit and scope of the invention as 25 claimed hereinafter.

Having described the invention what is claimed as new is:—

1. A method of repairing cracks in castings, 30 consisting in first placing in the crack a cementitious compound and subsequently driving into the crack a wedge of ductile material and hammering the outer portion of the wedge to flatten the same over the outer limits of the crack.

2. Means for repairing cracks in castings, comprising cementitious material disposed in the cracks and a wedge for cooperating with said material, said wedge having a recess in its end overlapping and confining the material.

3. A method of repairing cracks in castings, 40 comprising in first boring a hole in the casting at an end of the crack, then placing cementitious material in the crack and in the hole and subsequently driving into the crack a wedge of ductile material, said wedge having a projecting part at 45 one end for fitting over the material in the hole.

JOE LEMOS.
